UNITED STATES PATENT OFFICE.

ARTHUR E. PETERS, OF CANTON, OHIO.

SHEARING-MACHINE.

No. 923,298.

Specification of Letters Patent.

Patented June 1, 1909.

Application filed February 26, 1909. Serial No. 480,196.

To all whom it may concern:

Be it known that I, ARTHUR E. PETERS, a citizen of the United States, residing at Canton, in the county of Stark and State of Ohio, have invented a new and useful Improvement in Shearing-Machines, of which the following is a specification.

The invention relates to a machine for shearing sheets or plates of metal or other material, and is particularly directed to the hold-down mechanism whereby the sheets are clamped during the shearing operation.

The general object of the improvement is to couple the hold-down apron directly with the moving knife-holder by a friction clutch, whereby the apron is automatically operated by the reciprocating movements of the knife-holder. This general object and other particular benefits are attained by the mechanism, construction and arrangement illustrated in a preferred form of the machine set forth in the accompanying drawings, forming part hereof, in which—

Figure 1 is a perspective view of the shearing machine showing the improved hold-down mechanism applied thereto; Fig. 2, a front elevation of one end of the machine with part of the frame in section to show details of construction; Fig. 3, a vertical section 30 of the machine on line 3—3, Fig. 2, showing a few sheets therein and the normal position of the shearing and hold-down mechanism; Fig. 4, a similar section in plane 4—4, Fig. 1, showing the depressed or operative position 35 of the shearing and hold-down mechanism; Fig. 5, a horizontal section of one end of the machine on line 5—5, Fig. 4; Fig. 6, an enlarged section of the friction disks, showing the use of supplemental washers; and Fig. 7, 40 a fragmentary view showing the use of spring plungers for the feet of the hold-down apron.

Similar numerals refer to similar parts throughout the drawings.

The frame of the machine is composed of 45 the bed plate 1, on each end of which are secured standards 2, which standards are connected together by the back brace 3 on which is mounted the intermediate bracket 4. The table 5 is secured on the lower jaws 50 6 of the standards, and ways as 7 are provided in the standards, in which ways the ends of the upper knife-holder 8 are adapted to slide up and down. The lower knife 9 is formed or attached on the rear edge of the 55 table and the upper knife 10 is formed or attached on the lower front edge of the upper

knife-holder. The main shaft 11 is journaled in the bearings 12 and 12^a on the standards and intermediate bracket, and on this shaft are eccentrically journaled the pitmen 13 the lower ends of which are pivoted to the upper knife-holder at 14, by means of which the same is moved up and down in its ways in the operation of the machine.

The hold-down apron 15 is located immediately in front of the upper knife-holder and the ends as 16 of the apron are adapted to operate in ways as 17 which are provided in the respective slide-plates 18 which are formed or secured on the standards 2; which 65 plates preferably form the forward walls of the knife-holder ways 7, as shown in section in Fig. 5. The upward movement of the apron in its ways is limited by bumpers as 19, preferably made of resilient material, one 70 of which bumpers is secured in each way, preferably by means of the holder 20 which is held by the stud bolt 21 entered through the slotted aperture 22, and is adjusted by the gib key 23, as shown in sectional detail in 75 Fig. 2.

The hold-down shaft 24 is horizontally located and journaled in the bearings 25, preferably on the forward side of the apron; one or more pinions 26 are secured on this 80 shaft and extend through the openings 27 formed in the apron, and these pinions are adapted to mesh with the corresponding racks 28 formed or attached on the upper knife-holder. A series of disks 29 and 29^a 85 are mounted on the shaft and while being secured against rotation thereon as by the feather 30, they are free to move endwise along the shaft. One or more rings 31 are provided between the respective disks, preferably around the hubs as 32 which are 90 formed on certain disks, and these rings are held against rotation with the disks by means of the projecting shoulders 33 which abut the edges 34 of the opening in the apron. 100

The disks and rings are preferably located alongside the corresponding pinion, and are adapted to be compressed together against the pinion by means of the spiral spring 35 and the nut 36 which is screwed on the free 105 end of the shaft, preferably with the intervening washer 37. It is evident that by a suitable adjustment of the nut the friction between the disks and the rings can be varied at will, thus controlling the rotation of 110 the shaft in its bearings; and that by adjusting this friction to prevent a rotation of the

shaft, the apron will be normally sustained by the upper knife-holder through the engagement of the teeth of the racks and pinions.

5 In the operation of the machine, the sheets 38 are placed on the table with the edges extending underneath the feet 39 of the apron and beyond the edge of the lower knife, as shown in Fig. 3. The machine is then operated to lower the upper knife, the edge of which is normally located above the feet of the apron, and in so doing the apron also drops downward until its feet rest upon the sheet. It is evident that by reason of the 15 gearing connections, a further downward movement of the upper knife-holder will rotate the hold-down shaft, and that this rotation must overcome the friction of the disks and rings; so that the apron will impress the 20 sheets with a force equal to the weight of the apron plus the friction of the disks and rings, and the sheets will thereby be clamped firmly in position for the shearing operation which is accomplished by the continued downward 25 stroke of the upper knife-holder to the position shown in Fig. 4.

When the knife-holder is raised again, it is evident that the apron will be carried upward at once by reason of the friction of its coupling mechanism until its ends abut the bumpers, whereupon a further raising of the knife-holder serves to rotate the hold-down shaft by overcoming the friction of the disks and rings, which brings the parts in position 35 for another operation. It is evident that the apron is started upward just as soon as the upward movement of the knife-holder begins, so that the sheared sheets are promptly released and can be moved to insert other 40 sheets during the upward operation of the machine, thus saving time in this respect. And it is evident that the clamping action of the hold-down apron can be increased at will by merely increasing the pressure of the 45 disks against the rings by an adjustment of the compressing devices.

In practice, it is preferred to prevent undue wear of the disks and rings by oiling their contact faces, and it is also sometimes desirable to provide the intervening washers 40 of wood, fiber, bronze or other suitable material between the disks and rings as shown in Fig. 6, which serves to increase the friction and to reduce abrasion. The spring plungers 41 may also be provided in the feet 39^a of the hold-down apron, as shown in Fig. 7, which serve to cushion the clamping effect of the apron and to compensate for any variation in the thickness of the sheets. The 55 safety stops 42 may also be formed or secured on the upper knife-holder, which stops are adapted to operate in the openings 43 in the apron, and by abutting the upper ends 44 of these openings will serve to raise and support the hold-down apron in the event the 60

frictional mechanism fails to perform its functions, by reason of improper adjustment, accident or other cause. But it will be understood that these safety stops are not essential, nor are they intended to be operative 70 in the normal use of the machine. The apertures 45 and 45^a are preferably provided in the flanges of the slide plates and the ends of the apron, which apertures are so located as to register with each other when the apron 75 is raised to its inoperative position, in which position it may be held by inserting pins (not shown) through the apertures, and by loosening the friction devices it is evident that the machine can be operated without using 80 the apron.

What I claim as my invention, and desire to secure by Letters Patent, is—

1. In a shearing machine, a moving knife-holder and a reciprocating hold-down apron with bumpers to stop the upward movement of the apron; and a friction coupling between the knife-holder and the apron including a rotatable shaft on the apron, a pinion on the shaft, a rack on the knife-holder meshing with the pinion, disks feathered on the shaft with intervening non-rotatable rings, and adjustable means for compressing the disks and rings together. 90

2. In a shearing machine, a moving knife-holder and a reciprocating hold-down apron with bumpers to stop the upward movement of the apron; and a friction coupling between the knife-holder and the apron including a rotatable shaft on the apron, a pinion on the shaft, a rack on the knife-holder meshing with the pinion, disks feathered on the shaft with intervening non-rotatable rings, and means for compressing the disks and rings together. 100

3. In a shearing machine, a moving knife-holder and a reciprocating hold-down apron with bumpers to stop the upward movement of the apron; and a friction coupling between the knife-holder and the apron including a rotatable shaft on the apron, a gearing connection between the shaft and the knife-holder, disks feathered on the shaft with intervening non-rotatable rings, and adjustable means for compressing the disks and 110 rings together. 115

4. In a shearing machine, a moving knife-holder and a reciprocating hold-down apron with bumpers to stop the upward movement of the apron; and a friction coupling between the knife-holder and the apron including a rotatable shaft on the apron, a gearing connection between the shaft and the knife-holder, disks feathered on the shaft with intervening non-rotatable rings, and means 120 for compressing the disks and rings together. 125

5. In a shearing machine, a moving knife-holder and a reciprocating hold-down apron with bumpers to stop the upward movement of the apron; and a friction coupling between 130

- the knife-holder and the apron including a rotatable shaft on the one, a gearing connection between the shaft and the other, disks feathered on the shaft with intervening non-
5 rotatable rings, and adjustable means for compressing the disks and rings together.
6. In a shearing machine, a moving knife-holder and a reciprocating hold-down apron with bumpers to stop the upward movement
10 of the apron; and a friction coupling between the knife-holder and the apron including a rotatable shaft on the one, a gearing connection between the shaft and the other, disks feathered on the shaft with intervening non-
15 rotatable rings, and means for compressing the disks and rings together.
7. In a shearing machine, a moving knife-holder and a reciprocating hold-down apron with bumpers to stop the upward movement
20 of the apron; and a friction coupling between the knife-holder and the apron including a shaft adjacent thereto, a series of rotatable disks with intervening rings on the shaft, adjustable means for compressing the disks and
25 the rings together, a gearing connection between the rings and the knife-holder, and means coördinated with the apron for controlling the rotation of the rings with reference to the disks.
- 30 8. In a shearing machine, a moving knife-holder and a reciprocating hold-down apron with bumpers to stop the upward movement of the apron; and a friction coupling between the knife-holder and the apron including a shaft adjacent thereto, a series of rotatable disks with intervening rings on the shaft, means for compressing the disks and the rings together, a gearing connection between the rings and the knife-holder, and means
35 coördinated with the apron for controlling the rotation of the rings with reference to the disks.
- 40 9. In a shearing machine, a moving knife-holder and a reciprocating hold-down apron with bumpers to stop the upward movement of the apron; and a friction coupling between the knife-holder and the apron including a shaft adjacent thereto, a series of rotatable disks with intervening rings on the shaft, adjustable means for compressing the disks and the rings together, a gearing connection between the rings and the knife-holder, and means respectively coördinated with the knife-holder and the apron for controlling
45 the relative rotation of the disks and the rings.
- 50 10. In a shearing machine, a moving knife-holder and a reciprocating hold-down apron with bumpers to stop the upward movement of the apron; and a friction coupling between the knife-holder and the apron including a shaft adjacent thereto, a series of rotatable disks with intervening rings on the shaft, means for compressing the disks and the rings together, a gearing connection between
55 the rings and the knife-holder, and means coördinated with the apron for controlling the rotation of the rings with reference to the disks.

the rings and the knife-holder, and means respectively coördinated with the knife-holder and the apron for controlling the relative rotation of the disks and the rings.

11. A friction coupling between the moving knife-holder and the hold-down apron of a shearing machine, including a rotatable shaft on the apron, a pinion on the shaft, a rack on the knife-holder meshing with the pinion, disks feathered on the shaft with intervening non-rotatable rings, and adjustable means for compressing the disks and rings together. 70

12. A friction coupling between the moving knife-holder and the hold-down apron of a shearing machine, including a rotatable shaft on the apron, a pinion on the shaft, a rack on the knife-holder meshing with the pinion, disks feathered on the shaft with intervening non-rotatable rings, and means for compressing the disks and rings together. 80

13. A friction coupling between the moving knife-holder and the hold-down apron of a shearing machine, including a rotatable shaft on the apron, a gearing connection between the shaft and the knife-holder, disks feathered on the shaft with intervening non-rotatable rings, and adjustable means for compressing the disks and rings together. 90

14. A friction coupling between the moving knife-holder and the hold-down apron of a shearing machine, including a rotatable shaft on the apron, a gearing connection between the shaft and the knife-holder, disks feathered on the shaft with intervening non-rotatable rings, and means for compressing the disks and rings together. 95

15. A friction coupling between the moving knife-holder and the hold-down apron of a shearing machine, including a rotatable shaft on the one, a gearing connection between the shaft and the other, disks feathered on the shaft with intervening non-rotatable rings, and adjustable means for compressing the disks and rings together. 105

16. A friction coupling between the moving knife-holder and the hold-down apron of a shearing machine, including a rotatable shaft on the one, a gearing connection between the shaft and the other, disks feathered on the shaft with intervening non-rotatable rings, and means for compressing the disks and rings together. 115

17. A friction coupling between the moving knife-holder and the hold-down apron of a shearing machine, including a shaft adjacent thereto, a series of rotatable disks with intervening rings on the shaft, adjustable means for compressing the disks and the rings together, a gearing connection between the rings and the knife-holder, and means coördinated with the apron for controlling the rotation of the rings with reference to the disks. 120

18. A friction coupling between the mov- 130

- ing knife-holder and the hold-down apron of a shearing machine, including a shaft adjacent thereto, a series of rotatable disks with intervening rings on the shaft, means for compressing the disks and the rings together, a gearing connection between the rings and the knife-holder, and means coöordinated with the apron for controlling the rotation of the rings with reference to the disks.
19. A friction coupling between the moving knife-holder and the hold-down apron of a shearing machine, including a shaft adjacent thereto, a series of rotatable disks with intervening rings on the shaft, adjustable means for compressing the disks and the rings together, a gearing connection between the rings and the knife-holder, and means respectively coöordinated with the knife-
- holder and the apron for controlling the relative rotation of the disks and the rings. 20
20. A friction coupling between the moving knife-holder and the hold-down apron of a shearing machine, including a shaft adjacent thereto, a series of rotatable disks with intervening rings on the shaft, means for compressing the disks and the rings together, a gearing connection between the rings and the knife-holder, and means respectively coöordinated with the knife-holder and the apron for controlling the relative rotation of 25 the disks and the rings. 30
